C. W. BARNABY.

KEY LEVER.

APPLICATION FILED JAN. 29, 1919.

1,331,689.

Patented Feb. 24, 1920.

INVENTOR.

Charles W. Barnaby.

UNITED STATES PATENT OFFICE.

CHARLES W. BARNABY, OF NEW YORK, N. Y.

KEY-LEVER.

1,331,689.

Specification of Letters Patent. Patented Feb. 24, 1920.

Original application filed October 28, 1916, Serial No. 128,248. Divided and this application filed January 29, 1919. Serial No. 273,865.

To all whom it may concern:

Be it known that I, CHARLES W. BARNABY, a citizen of the United States, and a resident of the borough of Richmond, county of Richmond, city and State of New York, have invented certain new and useful Improvements in Key-Levers, of which the following is a specification.

My invention relates to the operating mechanism of typewriting machines and the like and the objects of my invention are to provide a key lever of simple, cheap and superior form. The present application constitutes a divisional application of my co-pending application, Serial No. 128,248, filed October 28, 1916.

Figure 1 is a plan view of a key lever blank cut from a metal sheet.

Fig. 2 is a perspective view of the key end of Fig. 1 after being shaped to receive a key-
rim.

Fig. 3 shows another application of my invention to the key blank.

Fig. 4 is a perspective view of Fig. 3 after the key flange is formed into shape.

Fig. 5 is still another application of my invention to a key blank.

Fig. 6 is a perspective view of Fig. 5 after the key flange is formed into shape.

Fig. 7 is a still further application of my invention to a key blank.

Fig. 8 is a perspective view of Fig. 7 after the key flange is formed into shape.

Figs. 9, 10 and 11 are top, side and end views of the pivot portion of the lever Fig. 1.

Figs. 12 and 13 are top and side views of the pivot portion of the lever Fig. 1 where in the two pivot lobes are bent along different lines from those which resulted in the relation of the pivot lobes in Figs. 9, 10 and 11.

Fig. 14 shows approximately the lines upon which the lobes of the blank are bent to give the position to the lobes shown in Figs. 12 and 13.

In the formation of a lever with integral key flange by means of cutting a blank from a sheet of metal as illustrated in Fig. 1 and where it is desirable to have the key flange 2—4—4 approximately centered on the key stem 3, the slots 7—7 cut in the blank to carry the stem 3 to the center 1 of the circular flange represented by 2 and the dotted

lines 4—4 leave a considerable gap in the 55 side of the circular key flange so that when the blank is bent on the line 1 to throw the plane of key flange 2—4—4 to a position at right angles with respect to the plane of the stem 3, a considerable portion of the key rim 60 and pad is left unsupported. In the application of my invention I elongate one or more of the key flange lobes, as at 5—6, and after the key flange is bent to its right angle position I bend the elongated lobe or lobes 65 to a position to close the gap in, and complete the periphery of the key flange, as illustrated in Fig. 2.

Fig. 3 illustrates an application of my invention in which a single elongated lobe 6 70 is provided at one side of and approximately parallel with the stem 3. This lobe may be provided for by a continuation of the stem in approximately a straight line, as shown by the dotted lines 6', or may be otherwise 75 located with respect to stem 3. Fig. 4 shows the key flange resulting from bending blank Fig. 3 on the line 8 to bring plane 2 at right angles to stem 3 and bending the lobe 6 to complete the periphery of the key flange. It 80 is desirable to provide a bracket 9 on the blank upon which the end of the lobe may rest when bent into position.

Fig. 5 illustrates another application of my invention in which the key end of the 85 blank is slotted to divide the main portion of the key flange into two portions 2 and 2'. 2 is given a right angle bend forward and 2' a right angle bend backward along the dotted line. The lobes 5 and 6 are bent to 90 complete the contour of the flange which results in the formation of the key flange shown in Fig. 6.

Fig. 7 illustrates an application of my invention in case a double stem is desired. 95 It also illustrates how, where two lobes are employed, one may be elongated, as at 5, and the other, 6, normally shaped; or how both lobes, as 5' and 6', may be elongated. Each stem 3 and 3' is given a right angle bend 100 downward leaving the plane of the flange 2—2' undisturbed. Lobe 5 is then bent to meet lobe 6 and lobes 5' and 6' are bent to meet each other. The result is a key flange carried by a double stem as shown in Fig. 8. 105

Fig. 1 illustrates how the two bearing lobes are formed side by side on the lever blank. By bending lobe 10 backward on

the line 12 and upward on the line 11, and then bending lobe 10' forward on the line 12' and upward on the line 11', the two side by side lobes 10—10' are thrown into spaced, 5 face to face relation with the axes of pivot bearings 15—15' coinciding with a common center line perpendicular to the plane of the body of the lever, as illustrated in Figs. 9, 10 and 11.

10 Referring to Fig. 14: by bending lobe 10 forward and lobe 10' backward and upward on the lines 13, 12, 13' and 12', respectively, the two lobes are thrown into spaced, face to face relation with the axes of their pivot 15 bearings coinciding with a common center line which lies at an angle of approximately 45° with respect to the plane of the body of the lever, as illustrated at 14—14' Fig. 12, and shown in side view Fig. 13. Thus, 20 through my invention, by the formation and location of lobes in the plane of a sheet blank and bending same on certain lines, I am enabled to provide a lever with spaced pivot bearings whose coinciding axes lie at 25 any desired angle with respect to the plane of the body of the lever from 90° to 45° or less, and a key flange of practically unbroken periphery.

This invention is also disclosed, in a 30 measure in my copending applications, Serial Nos. 112,951, typewriters, filed August 3rd, 1916, and 169,676, escapement, filed May 19th, 1917.

I claim—

1. A key bar cut from sheet metal, a key flange portion on said bar adapted to be bent to a plane transverse to the plane of said bar, and an arm projecting from said key-flange portion adapted to be bent to bridge the gap left in said key-flange by the bar 40 portion of said key bar. 35
2. A key bar cut from sheet metal and including a body portion and a flange portion, said flange portion being adapted to be bent to a plane transverse to said body 45 portion and to be bent to bridge the gap left in said flange portion by said body portion, thereby forming a key-flange of approximately complete contour.
3. A key bar cut from sheet metal and including a key-flange portion of incomplete circular contour, said key-flange portion being adapted to be bent to a plane transverse to said body portion and formed to an approximately complete circular contour. 50
4. A key operated lever blank cut from sheet metal, two contiguous pivot lobes on said blank, said lobes being adapted to be bent on different predetermined lines to 60 provide two axially spaced pivot bearings so positioned as to place the axis of said bearings at any predetermined one of the various possible angles with respect to the plane of said lever blank.

CHARLES W. BARNABY.
